UNITED STATES PATENT OFFICE.

JOSEPH BECKER, OF PITTSBURGH, PENNSYLVANIA, ASSIGNOR TO THE KOPPERS COMPANY, OF PITTSBURGH, PENNSYLVANIA, A CORPORATION OF PENNSYLVANIA.

COKE-OVEN-CHARGING CAR.

1,376,313.

Specification of Letters Patent. Patented Apr. 26, 1921.

Application filed December 2, 1918. Serial No. 264,964.

To all whom it may concern:

Be it known that I, JOSEPH BECKER, a citizen of the United States, and residing in Pittsburgh, in the county of Allegheny and State of Pennsylvania, have invented a new and useful Improvement in Coke-Oven-Charging Cars, of which the following is a specification.

This invention relates in general to coking plants and has more particular reference to the provision of effective means for taking care of the smoke incidental to the charging or recharging of a heated coking oven.

In the coking of coal each charge as completely coked is pushed from the coking chamber and a succeeding charge is deposited therein immediately. There is of course a high temperature in the oven chamber and as the coal is poured in considerable smoke is evolved which is commonly discharged directly from the charging holes and ascension pipes of the ovens into the open air.

This invention has for a principal object the provision of simple apparatus in a coking plant for carrying off this smoke, so that it may be led to the stack of the battery or any other stack or to a smoke consumer; usually it is led into the battery stack where it is discharged at such height that the smoke nuisance to labor or vegetation is eliminated.

A further object of the invention is the provision of a charging apparatus provided with means for accomplishing this result which will be of simple construction and not require a considerable amount of attention in its operation.

A further object of the invention is the provision of means for taking care of the smoke incidental to charging and recharging without altering in any particular the construction of the coking ovens themselves and with the mere addition to the stationary equipment of a main for carrying off the smoke delivered by the charging device.

Other objects and advantages of the invention will be apparent as it is better understood from the following description when considered in connection with the accompanying drawing illustrating a preferred embodiment thereof.

On the drawing,

Figure 1 is a vertical section through top of a coking chamber showing a charging truck or car in elevation;

Fig. 2 is a top plan view of the car shown in Fig. 1; and

Fig. 3 is a side elevation of the car with the tops of the series of coking chambers shown in section.

For the purpose of illustrating my invention I have shown on the drawing a battery of coking ovens composed of individual coking chambers 11 of certain preferred construction. In accordance with the general practice each of these chambers has a series or set of openings 12 in its top, said openings being normally closed by the usual lids or covers. At one side, preferably the pusher side, the apparatus generally designated at 13, 14 is provided to carry off the coke oven gas to a by-product plant for storage and for distribution.

In accordance with my present invention a smoke main 15 is mounted on suitable supports 16 along the other side of the battery and this smoke main is provided with an inlet opening 17 opposite each coking chamber. In the present instance it is intended that the smoke incidental to the recharging operation will be conveyed from the coking chamber being charged to the smoke main by way of the openings 12 and the charging truck or car which is depositing a new charge of coal. Two tracks 18 extend along the top of the battery and across the several coking chambers and on these tracks the charging truck is propelled in any suitable manner.

The truck comprises a framework, built of structural metal, a base consisting of channel irons 19 and I-beams 21. The base is supported upon wheels 22 journaled in suitable bearing brackets 23 from the I-beams 21.

The charging car or truck in the present instance is provided with four hoppers 24 of general funnel shape and carried in a supporting framework 25 of angle iron or other structural metal construction. The bottoms of the hoppers are located at spaced intervals and are adapted to be disposed directly over the four openings 12, shown on the drawing. Each hopper is normally closed at its bottom by a slide 26 beneath which is located a chute 27, about the bottom of

which is provided an extensible sleeve 28 adapted to be projected into an appropriate opening 12 of the coking chamber. When a slide 26 is moved from closed position the charge in the corresponding hopper is emptied through the chute into the coking chamber 11.

This invention contemplates the use of the chutes to carry off the smoke of recharging and to this end these chutes are connected with the smoke main 15. A smoke flue 29 is carried upon the truck and from it branches 31 extend into the sides of the chutes. It is intended that the hoppers be opened severally or at least that they be not all opened at the same time, and to this end individual controlling means are provided for each hopper. This control comprises an operating lever 32 for each hopper pivoted at 33 on the truck frame and link 34 connected to said lever and to a second lever 35 also pivoted on the truck frame, at 36, which second lever is connected by a link 37 with the slide 26. The several levers 32 are disposed in a cab 38 in which the attendant in control of the truck stands. This cab 38 is centrally located and the arms of levers 32 are offset, being rigidly fastened on pivotally mounted fulcrum shafts 39 so that operation of the levers results in a direct pull on the slides. The control for the extension sleeves 28 is also mounted in the cab and this consists of a pedal or lever 41 pivoted at 42 and connected by a link 43 with the arm 44 of a crossbar or fulcrum 45 having individual arms 46 connected to lifting eye bolts 40 on the sleeves 28, the arms 44 and 46 with the universal bar 45 forming in effect a multiple arm bell crank lever.

40 The flue 29 has an extension adapted for direct connection into the inlets 17 of the smoke main 15. This connection consists of a pipe 47 pivotally connected at 48 with the end of the main flue member. The outer end of the pipe 47 is turned down at 49 so that it may make proper connection into the inlets 17.

The action of recharging the coking chambers consists briefly in connecting the smoke flue with the smoke main and lowering the sleeves 28 and then the manipulation of the sliding levers, the inrush of coal from one or more of the hoppers causes the smoke to be delivered out of the other charging openings into the smoke flue 29 and if the hoppers are singly manipulated there are available three distributing openings throughout the recharging operation, it being understood that the corresponding hopper slides are closed as soon as each hopper is emptied.

It will be obvious that the smoke incidental to recharging the coking chambers is carried off for proper disposition, where the present embodiment of the invention is employed, without requiring any reforming or

alteration of the coke ovens themselves and through the mere provision of suitable appliances upon the charging car and a smoke main for connection to such appliances.

It is thought that the invention and many of its attendant advantages will be understood from the foregoing description, and it will be apparent that various changes may be made in the form, construction and arrangement of the parts without departing from the spirit and scope of the invention or sacrificing its most material advantages, the form hereinbefore described being merely a preferred embodiment thereof.

I claim:

1. The combination of a coking oven provided with a coking chamber having a plurality of recharging openings and provided with a stationary main for carrying off the smoke incidental to the charging of such chamber, means for charging the coking chamber through said openings individually and independently of each other, and means for collectively connecting said openings with said smoke main during a charging operation, whereby smoke may pass through all of said openings to said main; substantially as specified.

2. In a coke-oven battery, the combination with a plurality of cross-wise extending ovens, each having a plurality of recharging openings; of a fixed smoke main associated with and extending longitudinally of the battery; and a combined smoke-conveying and oven-charging mechanism movable longitudinally of the battery and embodying means for connecting with said smoke main a recharging opening, while recharging through another, whereby the smoke formed within the oven during the recharging thereof may pass freely to said smoke main; substantially as specified.

3. In a coke-oven battery, the combination with a plurality of cross-wise extending ovens, each having a plurality of recharging openings; of a track extending longitudinally above said battery; a fixed smoke main associated with and also extending longitudinally of the battery; a truck movable on said track and provided with oven-charging mechanism and with smoke-conveying mechanism for connecting, during recharging, all the recharging openings of an individual oven simultaneously with said smoke main; substantially as specified.

4. In a coke oven, the combination of a coking chamber having a plurality of recharging openings, a fixed smoke main associated with said coke oven; and a combined smoke conveying and oven recharging mechanism, embodying means for conveying smoke through one recharging opening to said smoke main, while recharging the oven through another, substantially as specified.

5. In a coke-oven the combination of a

- coking chamber having a plurality of recharging openings; a fixed smoke main associated with said coke-oven; and a combined smoke-conveying and oven-recharging mechanism embodying means, operable during recharging, for connecting said recharging openings collectively and simultaneously with said smoke main; substantially as specified. 50
- 10 6. In a coke-oven battery, the combination of a plurality of ovens, each having a set of recharging openings, a fixed smoke main associated with said battery, and movable combined smoke-conveying and oven-recharging mechanism embodying means for selectively connecting with said smoke main the several individual recharging openings of an oven being charged; substantially as specified. 55
- 15 7. In a coke oven battery, the combination with a plurality of coking chambers each having a plurality of smoke outlet openings, of a fixed smoke main associated with said battery and having smoke inlet 60 openings companion to the several coking chambers, and a truck movable longitudinally of the battery and provided with oven-recharging means and with a connection movable from coking chamber to coking chamber and into connection with an appropriate inlet opening in said smoke main, said connection being extensible to move down into position for collectively connecting a plurality of coking-chamber smoke 65 outlet openings simultaneously with the companion smoke inlet opening of the aforesaid smoke main. 70
- 20 8. A charging truck for a coke oven, comprising a plurality of hoppers each provided with a chute adapted for connection with a coking chamber being charged, and a smoke flue carried by the truck and connected with said chutes for conveying off the smoke incidental to a recharging operation. 75
- 25 9. A charging truck for a coke oven, comprising a plurality of hoppers each provided with a chute adapted for connection with the coking oven being charged, a smoke flue carried by the truck and connected with said chutes, and means for singly releasing the charges in said hoppers. 80
- 30 10. A charging truck for a coke oven, comprising a plurality of hoppers each provided with an extensible chute adapted for connection with the coking chamber being charged, a smoke flue carried by the truck and connected with said chutes, a common control for extending said chutes into connection with said coking chamber, and an individualized control for releasing the charges in said hoppers and for shutting off communication between said chutes and said smoke flue. 85
- 35 11. In a coke oven, the combination with a coking chamber having a plurality of recharging openings, of a fixed main associated with said coke oven and adapted to carry off the smoke incidental to the charging operation, means for charging the coking chamber through said openings, and means for collectively connecting said openings directly with said smoke main during a charging operation, whereby smoke may pass through all of said openings directly to said main; substantially as specified. 90
- 40 12. In a coke oven, the combination with a coking chamber having a plurality of recharging openings, of a fixed main associated with said oven and adapted to carry off the smoke incidental to the charging operation, and a charging apparatus for said coking chamber, embodying means for charging the coking chamber through said openings individually and independently of each other, and means for collectively connecting said openings directly with said smoke main during a charging operation, whereby smoke may pass through all of said openings to said main; substantially as specified. 95

In testimony whereof I have hereunto set my hand in the presence of two subscribing witnesses.

JOSEPH BECKER.
